CLAIM

The ornamental design for the hasp locking apparatus, shown and described.

DESCRIPTION

FIG. 1 is an isometric view of the present invention directed at a top left corner of the present invention;

FIG. 2 is a front elevational view of the present invention;

FIG. 3 is a bottom elevational view of the present invention;

FIG. 4 is a left side elevational view of the present invention;

FIG. 5 is a right side elevational view of the present invention; and,

FIG. 6 is a rear view of the present invention.

1 Claim, 2 Drawing Sheets

FIG. 1.FIG. 2.FIG. 3.

FIG. 4.

FIG. 5.

FIG. 6.
